Primary Examiner—Doris V. Coles*Assistant Examiner*—Stacia Cadmus*Attorney, Agent, or Firm*—Sidley & Austin[57] **CLAIM**

The ornamental design for a fairing for a truck roof, as shown and described.

DESCRIPTION

FIG. 1 is a perspective view of a fairing for a truck roof showing our new design;

FIG. 2 is a reduced front view thereof;

FIG. 3 is a reduced top view thereof;

FIG. 4 is a reduced left side view thereof, the opposite side view being a mirror image of that shown; and,

FIG. 5 is a reduced perspective view showing our design. The back of the fairing forms no part of the claimed design. In addition, the broken line showing of a truck, in FIG. 5, depicts environment and is not part of the claimed design.
